UNITED STATES PATENT OFFICE.

CHARLES E. HOPKINS, OF NEW YORK, N. Y.

MACHINE FOR MAKING CURVED STEREOTYPE PRINTING-PLATES.

1,286,322.

Specification of Letters Patent.

Patented Dec. 3, 1918.

Original application filed December 18, 1911. Serial No. 666,645. Divided and this application filed January 22, 1917. Serial No. 143,684.

To all whom it may concern:

Be it known that I, CHARLES E. HOPKINS, a citizen of the United States, residing at New York, in the county of New York and State of New York, have invented a new and useful Machine for Making Curved Stereotype Printing-Plates, of which the following is a specification.

This is a division of my application for patent, Serial No. 666,645, filed December 19, 1911.

This invention relates to improvements in mechanism for trimming and shaving curved stereotype printing plates, and for thereafter delivering the trimmed and shaved plates to the cooling mechanism.

The principal objects of the invention are to reduce the detail elements to a minimum as near as possible at the present time, to reduce the space occupied by all the elements necessary for finishing curved stereotype printing plates ready to be immediately attached to the cylinders of rotary web printing presses.

Among the objects of the invention are the following—A riser or slug is separated from the type portion of the stereotype plate by an entirely new principle, dispensing with the revolving planetary saw mechanism and the separate means for carrying the riser free from the machine. In order to accomplish this I employ a simple tool so mounted that it revolves at considerable speed about the axis of the knife shaft and simultaneously advances toward and through the stereotype plate (locked in the arch) from the concave or axis side and at the proper angle to form the necessary bevel while separating the riser from the type portion of the plate. During this operation the shaving knife shaft makes one complete revolution carrying the knife which trues up the ribs cast on the concave side and beneath the type face of the stereotype plate.

In this invention I employ a hand operated conveyer for moving the stereotype plate from the casting mechanism and positioning it in the finishing mechanism, and thereafter moving both the type face portion and the separated riser out of the finishing mechanism. The type face portion is moved over the revolving straight edge finishing cutters and into position on the cooling mechanism, and the riser is moved on the projecting

rails of the cooling mechanism. In this way the finished plate as well as the riser are delivered back in the same position as when picked up by the conveyer, and the conveyer is thus brought to proper position to engage the finished plate. The parts are also left directly in front of the operator so that he can pick up the riser and place it in a chute to convey it to the melting pot, then, in operation, he opens the valve controlling the flow of water to the cooler. Thereupon the water rushes into a distributing pipe positioned in the spray pipe and thereafter into engagement with the concave surface of the finished stereotype plate thereby cooling the plate so that it can be handled.

The invention also involves a safety locking means through which it is impossible to start the finishing mechanism if the conveyer or plate lifter is not in proper position or to raise a plate into position in the shaving arch unless it is in exact position to be finished. Means is also provided whereby the operation of the finishing mechanism can be checked at any time, and means for automatically stopping the finishing mechanism after each cycle.

Further objects and advantages of the invention will appear hereinafter.

Reference is to be had to the accompanying drawings in which—

Figure 1 is a side view of a machine constructed in accordance with this invention showing the cooling mechanism aligned with the finishing mechanism, part of the side frame being broken away to show interior construction;

Fig. 2 is a side elevation of the same showing the plate carrying frame supported over the inclined core and a stereotype plate (sectional) supported in the finishing mechanism, certain parts being in a longitudinal cross section;

Fig. 3 is a plan of the machine with the arch of the finishing mechanism removed, and part of the pouring sheet broken away;

Fig. 4 is a sectional view on the line 4—4 of Fig. 2 showing the stereotype plate resting on the side bars of the plate carrying frame;

Fig. 5 is a central longitudinal sectional view of a portion of the finishing mechanism showing the tail severed from the plate;

Fig. 6 is a transverse sectional view on the line 6—6 of Fig. 1 showing the finishing mechanism in elevation, and

Fig. 7 is an end elevation of the machine. 5 The invention is shown in a form comprising a frame A, an upright concave fixed back B, plate carrying frame C, core D, cooling device E, conveyer F, shaving arch G, and finishing device H. The concave back 10 as stated is mounted vertically between the two side frames at one end with its concave side facing the opposite end of the frame.

By combining the sides of the plate carrying frame C and matrix clamp bars, as 15 stated in my above mentioned original application, the stereotype plate P is formed with an extending lip P² along each outside straight edge; this lip is used as a guiding means during the action of conveying 20 the plate from the casting mechanism to and from the finishing mechanism, and is removed by edge trimming cutters. The plate carrying frame C is mounted on rollers 45 which operate on tracks 46 formed on 25 the top surface of the side frames A. These rollers 45 have studs which are mounted in bearings in brackets 47 formed on the side bars 48 of the frame. To the lower side ends of the side bars 48 are secured studs 30 49 carrying anti-friction rollers 50 which operate in vertical ways 51 on the side frames A.

The core D is pivoted to the frame A by the brackets 40 fast to its bottom end. These 35 brackets are mounted in bearings 53 on cross pieces 54. An inlet water pipe 55 and an outlet water pipe 56 are arranged at opposite ends of said hollow bearings on the brackets 40. The inlet pipe 55 enters the 40 water chamber 57 of the core at the bottom. The outlet pipe extends along the concave side of the core and into the chamber 57 near the top. Both the inlet and outlet pipes are provided with swivel joints 58 in 45 line with the core pivot axes. This permits the pipes to move with the movement of the core. A controlling valve 59 is positioned in the inlet pipe so that the operator can regulate the supply of water.

50 The convex face of the core D is provided with the usual grooves 660 forming ribs on the interior face of the plate P under the type matter and is also provided with a recess 67 on each side near the top for forming conveying lugs P' which co-act with the conveyer F as will be described hereinafter.

The side frames are provided with ledges 130 on which is supported the arch G slightly out of axial alignment with the 55 stereotype plate when it rests on the plate carrying frame in horizontal position. The interior circumference of the arch is slightly less than the exterior of the type face portion of the curved stereotype plate. The 60 driving shaft 131 of the machine operates 65

in bearings 132 formed upon the cross frame 133. On the driving shaft is a bevel gear 134 which meshes with and drives a bevel gear 135 fast on a short shaft 136. This short shaft operates in a bearing 137 formed 70 in the cross frame 133. Fast on this shaft 136 is a gear 138 meshing with a gear 139 loosely mounted on the knife shaft 140. The shaft 131 is provided with a worm 141 fast thereon which drives a worm gear 142 on 75 the knife shaft 140. In this way the knife shaft is driven slowly. The knife shaft is axially aligned with the arch and supported in bearings 143 at either end. A shaving knife 144 is fixed to a flange 145 formed 80 along that portion of the knife shaft underneath the arch.

Loosely mounted upon the knife shaft 140 is a support 148. It is attached to and made to travel around with the gear 139, which is 85 loosely mounted on the knife shaft as has been stated. On this support is a tool holder 149 set at an angle. Extending beyond the arch and knife and underneath where the riser portion of the stereotype plate rests 90 when in position to be shaved and trimmed is a simple trimming tool 150 in the tool holder. Said tool and holder are carried by the support 148 loosely mounted on the knife shaft 140. Fastened to the knife shaft 95 bearing 143 on the frame 133 and axially positioned with respect to the knife shaft is a round box or cover 151. This envelops the gear 139 and is provided with a cam groove 152 formed in its internal face. 100 Loosely keyed on the knife shaft 140 so as to rotate with it is a sleeve 153. One end of the sleeve is shaped to form a disk 154 and to the opposite end is fastened an arm 155 carrying a roller 156 which operates in 105 the cam groove 152. The disk 154 is made to operate in a groove 157 formed in and near the inner end of the tool holder 149. Upon each revolution of the knife shaft the cam 152 causes the disk to advance slowly, 110 thereby causing the tool to pass through the stereotype plate, separate the riser, and thereafter quickly return.

It will be seen that while the knife is caused to make one revolution with its shaft 115 140, the trimming tool 150 is caused to revolve at considerable speed about the axis of the knife shaft 140, and to advance simultaneously at the proper angle away from this axis until it engages the stereotype plate 120 held in the arch. It cuts its way through so as to separate the riser from the type face and properly bevel off the curved edge of the plate (see Fig. 5).

For the purpose of stopping the knife 125 shaft 140 and co-acting mechanism after each cycle of operations, the following mechanism is shown:—A clutch mechanism is provided between the driving pulley 160 and the driving shaft 131 on which this 130

pulley is loosely mounted. This clutch mechanism comprises a movable jaw 161 on the driving shaft, and an opposite jaw 162 fixed to a sleeve 159 loose on the shaft 131. 5 The movable jaw is caused to travel with the shaft through a sliding key 163. The sleeve 159 extends through the shaft bearing and the driving pulley 160 which is keyed to it so that when the clutch jaws are disengaged the pulley 160 and its co-acting jaw 162 can continue to run while the knife shaft and co-acting parts are at rest.

The clutch is held out of operation by the following mechanism:—A roller 164 is 15 fast on a cross bar 165 and engages in a groove 166 of the slide jaw 161. A pin 167 positioned on the face of the knife shaft worm gear 142 engages a projection 168 on the cross bar 165. The cross bar is forced 20 toward the engaged position by a spring 169. The clutch end of the cross bar is positioned against the rear cross shaft bearing 132. It operates about a stud 181 fast on said bearing. The front end, however, is 25 made to operate in a slot formed on the front bearing 132. Therefore, the cross bar can be lowered sufficiently to release its projection 168 from engagement with the pin 167 on the worm gear. This cross bar 165 30 is held in raised position by a connecting link 184. Said link is connected by a stud 185 to an arm 186 fast on a trip treadle shaft 187. On this shaft is a trip 188 which is pressed down to pull down the connecting 35 link and disengage the cross bar projection 168 from engagement with the stop pin 167 on the worm gear, thereby releasing that part of the mechanism.

On the main driving shaft 131 is the main 40 driving pulley 160 which by a belt drives a flanged pulley 123 on the end of a shaft 125 supported in a bracket 126 fixed to the frame A. When the cooler is alined in position to receive a plate, a friction pulley 127 on the 45 shaft 125 engages another friction pulley 128 mounted on a shaft 129. The shaft 129 is positioned near the ends of the cooler frame in bearings, (see Figs. 1 and 4) and upon it are mounted two opposite rotary 50 circular straight edge cutters K which are let into the guide way.

I will now describe the mechanism F illustrated in the drawings for conveying, lifting and locking the stereotype plate in position in the arch, and thereafter conveying it back to the edge trimmers and water cooling mechanism. The stereotype plate lifter and guide ways consists of two long bars 170 and 171 arranged with their edges 55 nearly alined with, but below, the straight edges of the arch G and tied together by cross bars 172 at each end. The plate lifting frame is pivoted to brackets 173 (Figs. 3 and 7) which are fast on ledges formed at 60 the top of the rear side frame A. The front

side of the lifter frame is supported by a 70 stud operating in one end of an arm 174, the opposite end being joined by a stud 175 to one end of a second arm 176, extending upward from a rock shaft 177. This consequently forms a toggle mechanism through 75 which the operator can raise the lifter and stereotype plate into position in the arch by moving a lever 178 fast on one end of the said shaft 177.

Extending across the machine is a rock 80 shaft 180 operated by a hand lever 281. On this rock shaft and alined with the plate lifter are fixed telescoping arms 282, the top of these arms being joined by a 85 stud 283 to slide pieces 284. These slide pieces are moved back and forth in recesses 285 formed on the inside faces of the bars 170 and 171 by the aforesaid connections. To the slide pieces 284 are fastened extending 90 arms 286 each having a recess 287 into which engages the lug P of the stereotype plate to be conveyed. Positioning stops 288 are placed in the path of the arms 286 for the purposes of stopping the forward movement of the conveying mechanism so as to 95 properly position the stereotype plate beneath and within the arch ready to be lifted and thereafter shaved and trimmed.

For the purpose of preventing the machine 100 being put out of commission through any forgetfulness on the part of the operator, mechanism is provided in the form of safety stops, safety lugs, and trip to make it impossible to start the finishing 105 mechanism unless the different operations have been carried out in the proper order and to make it impossible to move any part of the machine by hand during the cycle of movement after it has been started. The 110 conveyer must move forward and come into contact with stops 288 on the frame and the plate lifter must be elevated before the operator can trip and thereby start the mechanism. The act of tripping the starting 115 mechanism locks the plate lifter in its elevated position, and at the same time locks the conveyer and it becomes impossible to move either the lifter or conveyer so long as the mechanism is in motion. If it is necessary, however, for any cause to stop the mechanism before it finishes its cycle of 120 operation, the operator simply steps on a trip treadle and the mechanism comes to rest. This mechanism will now be described.

On the toggle arm 176 is positioned a bar 190 to engage a bearing 191 formed on the face of the front telescope arm 282 at all times except when the conveyer is in engagement with the positioning stop 288, in 125 which position, the bearing 191 is beyond the forward end of the bar 190 and the plate lifter can be elevated by the straightening out of the toggles which straightening moves the forward end of the bar 190 be- 130

4

yond the bearing 191 on the face of the telescope arm and thereby locks the conveyer between the bearing 191 and the positioning stop 288. To prevent the movement 5 of the bar 190 from behind the bearing 191 on the telescoping arm during the operation of the machine, there is arranged on the end of the toggle shaft 177 a short arm 192. When the toggles are extended the 10 short arm 192 engages the end of a rocking lock arm 193 on a short shaft 194. On this shaft 194 also is an arm 195 connected to the cross bar 165. The operation of the bar 165 causes the lock arm 193 to move into 15 the path of the short arm 192 on the toggle shaft and locks the toggles in the extended position. At the same time a hook 196 positioned on the toggle shaft 177 will be disengaged from under a projection 197 20 formed on the arm 186 on the trip shaft 187 on which is located the trip treadle 188 for releasing the trip so that the operator can start the mechanism. As the mechanism nears the end of the cycle of motion the pin 25 167 on the gear 126 engages the projection 168 on the cross bar 165 and forces the bar to withdraw the clutch jaws from engagement whereupon the mechanism stops. In case it should become necessary to stop the 30 mechanism before the end of the cycle the operator pushes down heavily on the trip treadle 188. This movement causes the arm 186 to act with the treadle movement and bring a projection 198 into engagement 35 with the connecting link 184 between the arm 186 and the cross bar 165. This causes the bar 165 to be forced forward so as to throw the movable member of the clutch out of engagement. The treadle 188 is provided 40 with a counterbalance weight 200 to hold the pedal and connecting parts in operative position.

The operation is as follows:—Starting with the casting chamber open and the core 45 D withdrawn in the position shown in Fig. 2, the operator, having positioned the matrix, now releases the locking hook 115 which holds the core in open position whereupon the core counter-balance 110, which is connected with the core by a flexible connection 50 111, is free to swing down. This pulls up on and causes the said core to rise and swing inwardly on its pivots toward the back. This allows the plate carrying frame C to 55 turn on its pivots into vertical position within the back and the further movement of the core toward the back brings the plungers 86 on the side of the cooler into position. Then the operator pushes down on 60 the operating handle 83 and thereby locks the core and frame in position for casting.

The operator now fills the casting chamber, in any usual manner, as by means of a pump or ladle. After allowing the proper 65 time for cooling the operator presses down

on the handle 83 which acts to first unlock the locking device and thereafter separates the core D from the plate carrying frame C in which the cast plate is now held. If there is no cast in the finishing mechanism 70 H to be cooled during the solidifying of the metal in the casting chamber, the operator should open the water valve 59 to allow sufficient water to run into the cooler basin to act as a counter-weight to deliver the 75 cast plate.

The cast plate now being delivered with the plate carrying frame resting on the frame A the operator grasps the hand lever 281 and pushes toward the finishing mechanism. This moves the stereotype plate off the plate carrying frame C and positions it in the finishing mechanism H. Having the plate located he pushes in on the lever 178 to operate the toggles 174—176 and raise the 80 stereotype plate up into the locked position in the arch G. The plate is now in position for finishing. To start the finishing mechanism the operator pushes down lightly on the trip treadle 188. 90

While the finishing mechanism is operating he repositions the matrix for another cast or positions a new matrix, closes the casting chamber, and fills the chamber with metal. It is during this time that the finishing mechanism operates to separate the riser from the type face of the stereotype plate as well as to true off the ribs beneath the type face. The finishing mechanism having finished its cycle of operation stops 95 automatically as has been stated. The operator by first pulling out on the lever 178 lowers the toggle mechanism and allows the stereotype plate to come down from engagement with the arch. Then he reverses the 100 lever 281 and pushes the riser and type face portion out of the finishing mechanism over the straight edge tools and into position on the cooler. He picks up the riser and returns it to the melting pot through the ordinary chute, (not shown) or by hand, and then opens the water supply by pushing down on the push valve 104. As soon as the plate sufficiently cools, he lifts it free from the machine by hand and then proceeds 105 with the series of operations again. 110

Although I have illustrated and described a preferred embodiment of the invention showing details of the various mechanisms, I am aware that the principles of the invention can be carried out in other forms and with other details of construction without departing from the scope of the invention as expressed in the claims. Therefore I do not wish to be limited to all the details herein 115 shown and described, but what I do claim is:— 120

1. In a stereotype plate finishing machine, the combination with an arch for receiving the plate, a support adjacent to said arch, 130

and means for engaging the plate while on the support, moving it into the arch, and moving it back again on the support.

2. In a stereotype plate finishing machine, 5 the combination with a shaving arch for receiving a plate, a support substantially in axial alinement therewith for a plate, means for raising a plate in the arch, and means for engaging a plate on said support, moving it into the arch, retaining its engagement therewith, and moving it back again on the support.

3. In a stereotype plate finishing machine, the combination with a shaving arch for receiving a plate, means for moving the plate radially to seat it in said arch, a support nearly in axial alinement with said arch, and a conveyer for engaging a plate on said support, moving it into the arch, retaining its engagement with the plate while being moved radially, and moving the plate out of the arch.

4. In a machine for finishing curved stereotype plates, the combination of a plate 25 supporting arch, a knife shaft axially alined with said arch, a trimming tool operative at an inclination with respect to the knife shaft axis and within the radius of said arch, and means for revolving the knife shaft and trimming tool at different speeds for the 30 purpose set forth.

5. In a machine for finishing curved stereotype plates, the combination of a plate support, an arch, means for conveying a plate 35 from the support, to and beneath the arch, means for holding the plate in the arch, means for shaving the interior of the plate, means for separating the riser from said plate, and edge trimming tools.

40 6. In a stereotype plate finishing machine, the combination with a shaving arch, an axial shaft therein having a shaving knife thereon, a support adjacent to said arch for the plates, a reciprocating conveyer having a notch for receiving a projection on the plate while on the support, manually operated means for moving the conveyer in and through the arch to position the plate in the arch and thereafter move it back out of the 45 arch on said support, means for seating the plate in the arch while said conveyer is in operative engagement with said projection, and means for operating the shaving blade to shave the plate.

55 7. In a stereotype plate finishing machine, the combination of a driving shaft, a shaving shaft having a shaving blade fixed thereon, means for driving the shaving shaft slowly from the driving shaft, a support rotatably mounted on the shaving shaft, means for driving said support from the driving shaft at a higher rate of speed than the 60 shaving shaft, a cutting tool movably carried by said support, and means, caused to operate by the difference in velocity rota-

tion between the shaving shaft and support, for reciprocating said tool as it rotates.

8. In a stereotype plate finishing machine, the combination of a driving shaft, a shaving shaft driven thereby, a tool support rotatably mounted on the shaving shaft, means connected with the driving shaft for rotating the tool support at a different rate of speed than the shaving shaft, said support having a guide at an angle to its axis, a tool holder mounted to move along said guide, and means adjacent to said support for moving the tool holder out and in along its guide as the shaving shaft rotates.

9. In a stereotype plate finishing machine, 80 the combination of a shaving shaft, a tool support rotatably mounted on the shaving shaft, means for rotating the tool support with respect to the shaving shaft, said support having a guide at an angle to its axis, a 85 tool holder mounted to move along said guide, means adjacent to said support for moving the tool holder along its guide as the shaving shaft rotates, and stationary means for controlling the tool moving means.

10. In a stereotype plate finishing machine, the combination of a shaving shaft, a stationary bearing therefor, having an internal cam, a disk loosely keyed to said shaft and having means engaging said cam 95 whereby as the shaft rotates the disk will reciprocate axially, a support loosely mounted on said shaft, means independent of said shaft for rotating said support, said support having a guide at an angle to the 100 axis of the shaft, a tool holder movable along said guide and connected with said disk to be reciprocated thereby in its guide as the support rotates.

11. In a stereotype plate finishing machine, the combination of a shaving shaft, a stationary bearing therefor, a cam fixed to said bearing, a sleeve loosely keyed to said shaft and having means engaging said cam 105 whereby as the shaft rotates the sleeve will 110 reciprocate axially and having a disk thereon, a support loosely mounted on said shaft, means independent of said shaft for rotating said support, said support having a guide at an angle to the axis of the shaft, a 115 tool holder movable along said guide and connected with said disk to be reciprocated thereby in its guide as the support rotates, and means for automatically stopping the shaving knife shaft upon the completion of 120 one revolution.

12. In a machine for finishing curved stereotype plates, the combination of an arch, a shaft axially alined with said arch, a tool operated by said shaft and arranged 125 to operate from the inside of the plate to true out the concavity of the plate and a tool movable relatively to the first named tool but also operated by said shaft to separate the riser portion therefrom.

13. In a machine for finishing curved stereotype plates, the combination of a frame, an arch supported by said frame, a shaft supported by said frame and axially aligned with the arch, a shaving knife on the shaft, a trimming tool revolving about the axis of the shaft, and means for advancing the trimming tool toward the arch from the inside thereof.
- 10 14. In a machine for finishing curved stereotype plates, the combination of a plate support, a cutter aligned with the support, means for rotating the cutter and simultaneously advancing said cutter toward and through the said plate radially from the inside thereof.
- 20 15. In a machine for finishing semi-tubular stereotype plates, the combination of means for supporting a semi-tubular plate, a cutting tool support axially operative in said plate, and means for causing said tool to revolve about the axis of the plate and to advance outwardly toward and through the said plate so as to form a bevel on its curved 25 edge.
- 30 16. In a machine for finishing curved stereotype plates, the combination of a plate conveyer, a plate lifter, a starting mechanism, and means whereby the conveyer and lifter are interlocked to operate position by the starting mechanism.
- 35 17. In a machine of the character described, the combination of a finishing mechanism, a conveyer for conveying a plate into the finishing mechanism, means for operating the finishing mechanism, and means for preventing the starting of the finishing mechanism if the conveyer is not in proper position to bring a plate into position to be operated on by the finishing mechanism.
- 40 18. In a machine of the character described, the combination of a finishing mechanism, a conveyer for conveying a plate into the finishing mechanism, means for operating the finishing mechanism, and means for preventing the starting of the finishing mechanism unless the different operations are carried through in sequence.
- 50 19. In a machine of the character described, the combination with an arch, of a finishing mechanism adapted to operate on a plate in the arch, and a plate lifter for lifting a plate into proper position in the arch, of means for preventing the starting of the finishing mechanism if the plate lifter is not in proper position to raise a plate into position in the arch.
- 55 20. In a stereotype plate finishing machine, the combination of an arch, finishing mechanism in the arch, a conveyer for moving a plate into the arch, a plate lifter for moving the plate into registration with the finishing mechanism, means for operating the finishing mechanism, means whereby the machine can be stopped at any point during the finishing operation, and means for automatically stopping the machine on the completion of a cycle of operations.
- 60 21. In a stereotype plate finishing mechanism, the combination of an arch, a conveyer for moving a plate under the arch, a manually controlled lifter for lifting a plate into the arch from the conveyer, a starting device, and means whereby the act of setting the starting device into operation locks the plate lifter in its elevated position and at the same time locks the conveyer in position, whereby it is impossible to move the plate lifter or conveyer out of position while the machine is operating.
- 70 22. In a stereotype plate finishing mechanism, the combination of an arch, a conveyer for moving a plate under the arch, a manually controlled lifter for lifting a plate into the arch from the conveyer into registration with the finishing mechanism, a starting device, and means whereby the act of setting the starting device into operation locks the plate lifter in its elevated position and at the same time locks the conveyer in position, and a trip treadle having means for stopping the mechanism at any time during its cycle of operations.
- 80 23. In a stereotype plate finishing machine, the combination with a shaft having finishing means thereon, and an arch adjacent thereto for receiving a plate to be finished, of a pair of horizontal bars for engaging the edges of the plate, a toggle mechanism connected with said bars, and operating means for operating the toggle mechanism to raise the bars and lift the plate into the arch.
- 85 24. In a stereotype plate finishing machine, the combination with a shaft having finishing means thereon, and an arch adjacent thereto for receiving a plate to be finished, of a pair of horizontal bars for engaging the edges of the plate, a toggle mechanism connected with said bars, operating means for operating the toggle mechanism to raise the bars and lift the plate into the arch, and a conveyer movable into position under the arch for bringing a plate over said bars.
- 90 25. In a stereotype plate finishing machine, the combination with a shaft having finishing means thereon, and an arch adjacent thereto, of a pair of bars for engaging the edges of the plate, a toggle mechanism connected with said bars, means for operating the toggle mechanism to raise the bars and lift the plate into the arch, a conveyer movable into position under the arch for bringing a plate over said bars, the toggle levers being provided with a bar, and the conveyer having an arm which the last named bar engages at all times except when the conveyer is at its limiting position under the arch, and means for permitting the
- 100 110 115 120 125 130

operation of said toggle levers when the bar and arm are in contact.

26. In a stereotype plate finishing machine, the combination with a shaving arch and finishing devices therein, of a conveyer movable axially to bring the plate into position under the arch, means movable transversely to the motion of the conveyer for engaging a plate in the conveyer and bringing it to a seat in the arch, means whereby the operation of said movable means locks the conveyer in position, and means for locking the transversely moving means in its extended position when it has seated a plate in the arch.

27. In a stereotype plate finishing machine, the combination with a shaving arch and finishing devices therein, of a conveyer movable axially to bring the plate into position under the arch, means movable transversely to the motion of the conveyer for engaging a plate in the conveyer and bringing it to a seat in the arch, means whereby

the operation of said movable means locks the conveyer in position, means for locking the transversely moving means in its extended position when it has seated a plate in the arch, a trip treadle for starting the mechanism, and means for locking the trip treadle in inoperative position, the last named means being connected with the second named locking means to be disengaged thereby when the second named locking means is brought into operative position.

28. In a machine for finishing curved stereotype plates, the combination of an arch, a shaft axially alined with said arch, and a beveling trimming tool, movable relatively to and also with said shaft operative from the inside of a curved plate, and arranged to separate the riser and simultaneously bevel the curved edge of a plate for the purpose set forth.

In testimony whereof I have hereunto affixed my signature.

CHARLES E. HOPKINS.
